Attorney

Patented Sept. 9, 1924.

UNITED STATES PATENT OFFICE.

RAY J. HELLER, OF LANSING, MICHIGAN.

EARTH SCRAPER.

Application filed July 6, 1923. Serial No. 649,929.

To all whom it may concern:

Be it known that I, RAY J. HELLER, citizen of the United States, residing at Lansing, in the county of Ingham and State of Michigan, have invented certain new and useful Improvements in Earth Scrapers, of which the following is a specification.

This invention relates to earth scrapers, for road work or excavations or the like, and has for its object the production of a scoop or shovel body intended to be drawn along by horses or tractor force, and having parts of special construction and arrangement comprising a plurality of scraper blades of which at least one is adjustable with respect to the side walls, and having a top extending between the sides. It is believed that by the combination of a number of scraper blades, one in advance of another, and adjustable one with respect to another, packed sand or gravel of whatever weight or density may be readily handled. Furthermore, by having a top plate or member of suitable size and location, when the scraper becomes filled it will tilt up and cease its digging action instead of merely continuing and overflowing.

In the accompanying drawings the particular formation and disposition of the parts are illustrated, and Fig. 1 represents a view from the front and in perspective of the usual form of this invention, showing all parts assembled. Fig. 2 is a view from the front and in perspective of an important modified form of this invention showing the individual or smaller scraper blades arranged at the sides. All parts are shown assembled in this view. Fig. 3 is an inside view of the lower front corner portion of one side, and shows the auxiliary scraper blade pivotally connected with the side in such manner that when the scraper is drawn forward the blade will excavate, but when the scraper is drawn backward the blade will lift.

Throughout the drawings and explanation the same letter is employed to refer to the same part.

Considering the drawings, Fig. 1, there are shown the vertical divergent sides A and *a*, connected by the top B and the back *b*. Plate C secured in an inclined position adjacent to the back plate may be regarded as the bottom of the scraper, or an extension of the main scraper blade *c* to which

it is suitably secured. Angle irons D connect the plate C with the sides, and the plates and angle irons are secured by bolts *d*. While in practice removable bolts are employed, this invention is not limited to the use of bolts, and any parts desired may be riveted together in the common manner.

The front or auxiliary blade is marked E, and the angle irons connecting it with the sides are referred to by the letter *e*. The angle irons *e* are secured to the sides by bolts F, and it will be observed that there are several rows of boltholes *f* arranged in inclined lines to provide for the adjustment of the auxiliary blade with respect to the sides. It will be observed that, as shown in Figs. 1 and 2, the side holes *f* permit the auxiliary scraper or scrapers to be adjusted in a higher or lower position, and also in an advanced position with respect to the rear of the scraper.

Near the front edge of each of the sides A and *a*, will be noted the vertical rows of holes G. These holes are intended to be engaged by any suitable coupling device to connect the scraper with horses or a tractor. Through the sides will also be seen the horizontal rows of holes *g*, and these are intended for engagement with any desired hoisting mechanism by which the scraper may be raised and moved to dump into a truck or out of the excavation.

Considering the modification illustrated in Fig. 2, the sides are designated H and *h*, the top J, and the back *j*. The main scraper blade is marked K. It is attached to the bottom L by bolts *k*, and the bottom is secured to the sides by the angle irons and bolts shown and already explained. The angle irons are marked M and the bolts *m*. In the modification the auxiliary scrapers are individual plates N and N', and the inclined rows of holes O are shown in the side *h*, and there are similar rows of holes in the side H, for the adjustment of the individual auxiliary scraper blades N and N' separately. The angle irons and bolts used are the same as already described, and are of common form and operation. In the modification the vertical rows of holes near the edges of the sides for engagement with the draught appliances are designated P, and the horizontal rows of holes Q are provided as before for the hoist connections.

Considering Fig. 3, there is shown the

lower forward corner of a side R. There are inclined rows of holes *r* for the adjustment of the auxiliary blade carrier or angle iron S. The blade itself is marked T, and below it will be noted the stop bolt *t*. When the blade T is pivoted in one of the holes *r* of an upper row of holes, the stop bolt may engage one of the lower holes. While it is occasionally of advantage to pivot the scraper blades, or the scraper as a whole, this invention is in no sense limited thereto or to any special devices for attaining that end.

In the operation of this invention under what may be regarded as one of the natural conditions met with, let it be assumed that a gravel bank is to be excavated, and that the material is somewhat dense and heavy. It is believed to be readily discernible from the drawings that the auxiliary or advanced scraper being set at a higher level between the sides will take off the top layer or stratum of the gravel deposit, and the following main scraper blade will take up another layer, rendering the operation of taking up the whole scraper load much easier and consequently more rapid. The operation of the modification is the same, and the individual auxiliary scraper blades effectively loosen the top of the sand or gravel body for the action of the main scraper following. Oftentimes it is necessary to draw the scraper directly backward on the ground, and to avoid the retardation and dragging effect of the scrapers they may be pivoted as illustrated in Fig. 3. When so attached the scrapers will dig when drawn forward, but will lift and slide over the earth when drawn backward.

Having now described this invention, and explained the mode of its operation, what I claim is:—

1. In a scraper, the combination with the sides, of a top plate connecting the sides, a back plate connecting the sides, a downwardly inclined scraper blade secured to the sides adjacent to the back plate, the said top

plate extending over the said blade in a forwardly direction for a distance substantially equal to the extent of the said blade 50 in the same direction, and an auxiliary blade mounted in an inclined position in advance of the first mentioned blade.

2. In a scraper, the combination with the sides, of a top plate connecting the sides, a back plate connecting the sides, a downwardly inclined scraper blade secured to the sides adjacent to the back plate, the said top plate extending over the said blade for a distance substantially equal to the extent of the 60 said blade in the same direction, an auxiliary blade mounted in an inclined position in advance of the first mentioned blade, and the said sides having a vertical row of holes whereby the draft cable may be attached 65 higher or lower with respect to the said blades.

3. In a scraper, the combination with the sides, of a top plate connecting the sides, a back plate connecting the sides, a downwardly inclined scraper blade secured to the sides adjacent to the back plate, the said top plate extending over the said blade for a distance substantially equal to the extent of the 70 said blade in the same direction, an auxiliary blade mounted in an inclined position 75 in advance of the blade first mentioned, and means for adjusting the auxiliary blade in position.

4. In a scraper, the combination with the sides, of a top plate connecting the sides, a back plate connecting the sides, a downwardly inclined scraper blade secured to the sides adjacent to the back plate, the said top plate extending over the said blade, an auxiliary 85 blade mounted in an inclined position in advance of the blade first mentioned, and means for adjusting the auxiliary blade in a higher or lower position and in a forward or rearward position with respect to the 90 back plate.

In testimony whereof I affix my signature.

RAY J. HELLER.
